UNITED STATES PATENT OFFICE

CORNELIUS R. SADLER, OF BARBERTON, OHIO, AND HOWARD J. KERR, OF WESTFIELD, NEW JERSEY, ASSIGNORS TO THE BABCOCK & WILCOX COMPANY, OF BAYONNE, NEW JERSEY, A CORPORATION OF NEW JERSEY

CHAIN GRATE STOKER

Application filed October 5, 1926. Serial No. 139,583.

Our invention relates to chain grate stokers, particularly of the type in which air under pressure is supplied to the fuel on the grate, and will be best understood from the following description and the annexed drawings, in which Fig. 1 is a longitudinal section of a chain grate in the lower part of a combustion chamber with our invention applied thereto; Fig. 2 is a section on the line 10 2-2 of Fig. 1 with the central portion of the stoker broken away; Fig. 3 is an enlarged section on the line 3-3 of Fig. 2; Fig. 4 is an enlarged section on the line 4-4 of Fig. 2; Fig. 5 is a section on the line 5-5 of Fig. 1, 15 and Fig. 6 is an enlarged section on the line 6-6 of Fig. 1.

Like reference characters indicate like parts in the different views.

In Fig. 1, the illustrative embodiment has 20 the usual driving shaft 10 and driven shaft 11 spaced apart and provided with sprocket wheels 12 engaging the chain 13, this chain being made up of links, in the usual manner, to form the grate. The shaft 10 will be 25 driven in the usual manner to carry the upper run of the chain 13 to the left in Fig. 1.

In the form illustrated, the space between the upper and lower runs of the chain is 30 divided into compartments by cross beams or girders 14 provided with seals at the top and the bottom thereof contacting with the chain so as to prevent the ready flow of air from one compartment to another, this sealing arrangement being no part of our present invention and, therefore, requiring no further 35 description.

The side walls 15 and 16 of the furnace chamber are supported on metallic supporting structures, which, in the form illustrated, 40 also embody blast boxes by which air may be supplied in regulated quantities to the several compartments formed by the beams or girders 14 and their seals. In the form illustrated, one of these supporting structures is fixed and the other has a portion 45 thereof which is movable laterally, the fixed side being shown in Fig. 3 and the movable or expansion side shown in Fig. 4.

Referring to the part shown in Fig. 3, the 50 blast box structure is made up of outside

plates 17 and inside plates 18 connected to transverse castings 19, the latter acting as partitions to divide the blast box longitudinally into separate compartments, the opening 20 in each casting connecting the air supply with each of these compartments. The top of the inside plate 18 is spaced from the angle 21 to provide an opening from the blast box compartment into the space between the upper and lower runs of the chain grate 13. 55 Dampers 22 control admission of air from the lower part of the blast box into the separate compartments thereof.

The blast box structure on the opposite or expansion side is also made up of outside plates 23 connected to transverse castings 24 which, in turn, are arranged in a manner similar to that at the fixed side. Openings 25 are formed in each of these transverse castings and dampers 26 control the supply from 60 the source of the air blast into the compartments formed by the transverse castings.

At the inner side of this blast box structure on the expansion side are plates 27 which may be comparatively thin and light, 65 and an angle 28, the adjacent edges of these two parts being spaced to provide an opening from each air blast compartment into the space between the upper and the lower runs of the chain grate.

Connected to the plate 29 forming the top 70 of the blast box structure is a ledge plate 30, the wall 16 resting on this ledge plate and the plate 29. On the horizontal leg of the angle 31 forming a part of the blast box 75 structure rests a movable plate 32 having at its top an angle 33 to which is connected a grate side guide 34 which, in turn, has its top in sliding engagement with the bottom of the ledge plate 30. Vertical angles 32' 80 connect the plate 32 to the angle 33 and guide 34.

On the opposite or fixed side (Fig. 3) there is also a ledge plate 35 connected to the top plate 36 of the blast box structure and a 85 chain side guide 37, also connected fixedly to the blast box structure.

The beams or girders 14 each have one end connected by the angles 38 to a transverse casting 19 and similarly below the 90

lower run of the grate are beams 39 connected by angles 40 to the plates 18, the bolts holding the angles 40 to the beams 39 extending through horizontal slots in the beams 39.

Each of the beams 14 is connected to the movable wall made up of the members 32, 32', 33 and 34 by the angles 41 and the beams 39 are also connected to the plate 32 by angles 40 with the same bolt and slot arrangement as at the opposite ends of these beams.

This movable wall structure has openings therein corresponding to the openings in the blast box compartment formed by the transverse castings 24 and a duct 43 extends through each of these two openings to form a conduit from the blast box compartment to the space between the grates. In the form shown, the duct 43 is attached to the movable wall structure and is free to slide horizontally in a slip joint construction supported by the castings so as to permit horizontal motion of the duct 43 without breaking the joint. In the form illustrated, this slip joint construction is made up of a part 44 extending over the top and down the sides of the duct 43, this member being attached to angle 28 by the flange 44. A spacer 46 holds a liner 45 spaced from the inside of the member 44, and the end of duct 43 slides in this space. Similarly the plate 27 is bent outwardly at 47 and is provided with an angle 48 to form a space between one of its legs and the part 47 in which the bottom of duct 43 can slide.

On the beams 39 is a slide plate 49 on which the lower run of the chain is supported and the cross beams or girders 14 may be provided with longitudinal beams 50 connected between the beams or girders 14.

With the arrangement described, it will be obvious that the members 34 and 37 form side guides for the upper run of the chain and similarly the plates 18 and 32 form side guides for the lower run of the chain. Because the chain is subjected to varying temperatures, particularly when forced blast is used, it is desirable to permit the chain and its supporting structure, such as the shafts 10 and 11, to expand crosswise without disturbing the side guiding functions of the chain side guides. The arrangement which we have provided will permit this, since the movable wall shown in Fig. 4 is free to move horizontally in accordance with the expansion of the transverse beams or girders 14, one end of these girders being connected to the fixed blast box and the other to the movable wall. The beams or girders 39 will also partake of this expansion and contraction, but since they may not expand and contract to the same degree as the girders 14, the bolt and slot construction is provided. The links 65 of the chain 13 are provided with the usual

clearance between them, when first erected, so that, if the chain and its supporting parts expand only the usual amount, the position of the movable wall of Fig. 4 will not be affected. If, however, the chain and the beams or girders 14 are heated more than the usual clearance will tolerate, then the expansion of the beams 14 will move the movable wall to the right in Fig. 4 to provide additional clearance and, at the same time, will maintain the side guides for the chain in correct operative position. In other words, by our arrangement, we have provided means by which binding of the chain between the side guides will be prevented even when excessive expansion and contraction takes place, and this without, at any time, having more than the usual clearance between the links crosswise of the grate.

The duct 43 and its slip joint is provided so that motion of the movable wall portion of Fig. 4 will not disturb the connection between the blast box and the space between the upper and lower runs of the chain.

It will be understood that the duct 43 may have one end connected fixedly to the blast box and the other end movable in the movable wall.

It will also be understood that while we have shown our arrangement in connection with a forced blast grate, many of the features of our invention may be used where natural draft is used or where the air is supplied from beneath the lower run of the chain.

As shown in Figs. 5 and 6, the bearings for the shafts 10 and 11 which come at the fixed side of the construction are mounted in fixed bearings connected to such structure with collars or the like to prevent end motion of the shafts in such bearings. Preferably the driving worm gear 51 is connected to the shaft 10 at this side. The sprockets 12 are fixedly connected to their respective shafts and when such shafts expand with the heat, these sprockets are also carried to the left of Figs. 5 and 6. To permit this longitudinal motion of the shafts, due to the expansion, we arrange the bearings at the left-hand end of the shafts in Figs. 5 and 6 (which are on the expansion side of the structure) so that the shafts may move endwise through such bearings. With the arrangement described it will be noted that when the entire grate and its supporting and driving structure is unduly heated, the grate itself, the driving sprockets for it and the shafts for such sprockets can all move to the left in Figs. 5 and 6 when thus expanded, carrying with them the chain side guides 32 and 34.

The plate 32 forming the lower side guide on the expansion side is curved outwardly at 52, so that the links of the chain will not be caught on the ends of this guide. To hold the movable wall structure against longitudinal motion in the direction of the motion

of the chain grate, we provide the slip joint shown at the right of Fig. 2, a vertical member made up of the adjacent legs of the angles 53, 54 connected to the movable wall structure extending into the space formed between the angles 55, 56 connected to the fixed part of the blast box structure. It will be obvious that this arrangement will prevent the pull of the chain moving the movable wall structure longitudinally while, at the same time, permitting the wall structure to move toward and away from the fixed portion.

We claim:

15 1. In combination, a chain grate stoker having upper and lower runs, side guides for the opposite sides of the upper run, a fixed support on one side of the stoker to which the guide on that side is secured, a second support on the other side of the stoker to which said other guide is secured, a cross beam connecting said supports, and means movably supporting said second support whereby it may move laterally with respect 25 to the stoker upon expansion or contraction of said beam.

2. In combination, a chain grate stoker having upper and lower runs, fixed members on both sides thereof, side guides for the opposite sides of said upper run of the stoker, means including cross beams connecting the guides on said opposite sides, and means securing the guide on one side to the fixed member on that side, the guide on the other side and the fixed member on that side having sliding engagement with each other.

3. In combination, a chain grate stoker having upper and lower runs, side guides for the opposite sides of the upper run, a fixed support on one side of the stoker to which the guide on that side is secured, a second support on the other side of the stoker to which said other guide is secured, a cross beam connecting said supports, means movably supporting said second support whereby it may move laterally with respect to the stoker upon expansion or contraction of said beam, and means preventing movement of said second support longitudinally of the stoker.

4. In combination, a chain grate stoker having upper and lower runs, a fixed blast box along one side thereof, a side guide for the upper run of the stoker on the same side as the blast box, means movably supporting said guide to permit movement toward and from the blast box, and a duct connecting the box with the space between said runs, said duct being secured to said support and having an expansion joint with said box.

5. In combination, a chain grate stoker having upper and lower runs, side guides for the opposite sides of the upper run, a fixed support on one side of the stoker to which the guide on that side is secured, a second support on the other side of the stoker to which

the other of said guides is secured, a cross beam connecting said supports, means movably supporting said second support whereby it may move laterally with respect to the stoker upon expansion or contraction of said beam, a fixed blast box along one side of the stoker, and a duct connecting the blast box with the space between said runs, said duct being secured to said second support and having an expansion joint with the box.

6. In combination, a chain grate stoker having upper and lower runs, fixed members on both sides thereof, side guides for the opposite sides of said upper run of the stoker, cross beams connecting the guides on said opposite sides, means securing the guide on one side to the fixed member on that side, means forming a sliding joint between the guide on the other side and the fixed member on that side, shafts at opposite ends of the stoker and adapted to operate the same, fixed bearings for said shafts on one side of the grate, and means on the other side of the grate supporting the other ends of the shafts but permitting movement thereof longitudinally of the shafts.

7. In combination, a chain grate stoker having upper and lower runs, a fixed blast box along one side thereof, a side guide for the upper run of the stoker on the same side as the blast box, means movably supporting said guide to permit movement toward and from the blast box, a duct connecting the box with the space between said runs, and means expansibly connecting said duct to said support and to said box.

8. In combination, a chain grate stoker having upper and lower runs, side guides for the opposite sides of the upper run, a fixed support on one side of the stoker to which the guide on that side is secured, a second support on the other side of the stoker to which said other guide is secured, a cross beam connecting said supports, means movably supporting said second support whereby it may move laterally with respect to the stoker upon expansion or contraction of said beam, a fixed blast box along one side of the stoker, a duct connecting the blast box with the space between said runs, and means expansibly connecting said duct to said second support and to said box.
